MARKING DEVICE

Samuel A. Hamnett, Los Angeles, Calif.; Aurora
Christina Hamnett executrix of said Samuel A.
Hamnett, deceased

Application March 28, 1944, Serial No. 528,429

6 Claims. (Cl. 101—17)

This invention relates to a marking device. The general object of the invention is to provide an improved marking or punching device which includes a handle or support member and wherein movable type are employed and wherein novel means is provided for holding the type in the marker.

A further object of the invention is to provide a novel type holder for a marking device.

Another object of the invention is to provide a type holder including a novel slide member for holding the type in place.

An additional object of the invention is to provide a marking device including a slidable type holder and including a novel means permitting the type holder to be assembled and manipulated to secure and remove type therefrom.

Other objects and advantages of the invention will be apparent from the following description taken in connection with the accompanying drawing, wherein:

Fig. 1 is an isometric view, with parts broken away, showing my new marking device;

Fig. 2 is a longitudinal, fragmentary, central sectional view showing the device;

Fig. 3 is a transverse section taken on line 3—3, Fig. 2;

Fig. 4 is a fragmentary section taken on line 4—4, Fig. 3;

Fig. 5 is a view similar to Fig. 2 showing the type holding member moved to outward position, and

Fig. 6 is a view similar to Fig. 5 showing one of the type members in position.

Referring to the drawing by reference characters, I have shown my invention as embodied in a marking device which is indicated generally at 10. As shown the device includes a handle 11 and a type holding device 12.

The handle is provided with a chamber 13 which has side walls 14, an inner end wall 15 and a top wall 16. The bottom and the outer end of the chamber are open.

The wall 16 of the chamber is provided with a plane inner face 17. Opposed grooves 18 are disposed in the side walls 14. The top wall 16 of the chamber is provided with an elongated slot 19 which has arcuate ends 20 and 21. The top wall is provided with a countersunk circular recess 22 which intersects the end 21 and the slot 19.

The type holding device 12 has peripheral beads 23 which fit in the grooves 18 in the side walls 14 of the holder. The type holder is provided with a cylindrical hole 24 which has a bottom

wall 25. The type holder is also provided with a pocket 26 which is defined by side walls 27 and end wall 28 with semi-cylindrical notches 29 at the juncture of the side walls 27 and the end wall 28. The type holder further includes a transverse rib 30.

The type holder is of a size to slide into the chamber in the handle and in assembly a holding pin 31 is arranged in the hole 24. This pin 31 has a cylindrical lower portion 32 slidable in the hole 24 and has a reduced upwardly extending portion 33 which is of slightly less diameter than the width of the slot 20. The member 31 includes a bottom recess 34 in which a spring 35 is fitted.

In assembly the member 31 is inserted in the hole 24 and is normally urged outwardly by the spring 35. The thickness of the wall 25 plus the overall height of the member 31 is slightly less than the depth of the chamber 13 so that when the pin is fully depressed it will pass beneath the inner face of the bottom 13 of the holder and will slide along the inner face until the pin aligns with the slot 20 whereupon the pin will spring outwardly into the slot thus preventing accidental outward movement of the type holder.

When the holder is moved inwardly the pin will move along the slot until the portion 32 of the pin is aligned with the recess 22 whereupon the spring will move upwardly, causing the portion 31 to enter the recess 22 to hold the type member in retracted type securing position.

My invention is used with type which include a body 40 and a transverse groove 41 which fits the rib 30. The type member has a suitable character 42 thereon.

In placing the type members in the holder the member is depressed and the type holder is moved outwardly. The proper type are then inserted with the slots 41 fitting the rib 30. After the type are assembled the holder is moved into the chamber until the pin is pushed into the hole by the spring 35 whereupon the parts become assembled.

From the foregoing description it will be apparent that I have invented a novel marking device which is made of a minimum number of parts, is of simple construction, readily assembled and is sturdy so that it will stand heavy use.

Having thus described my invention, I claim:

1. In a marking device, a body member including a handle portion having a chamber therein, a type holding member, means to mount said type holding member for sliding movement in the

chamber, said type holding member having a hole extending downwardly from the upper surface, a pin slidable in said hole, and means normally urging the pin upwardly in the hole, said body having an elongated slot positioned to receive said pin, said body having an inwardly open recess, said recess being of a size to receive a portion of the pin, the total length of the pin being no greater than the depth of said hole whereby the pin may be depressed inwardly so that its outer end is below the inner face of the top of the handle chamber to permit assembly and disassembly, said pin being slidable in said slot to permit said type holding member to be moved so that the type may be inserted, said type holding member having a type receiving pocket therein.

2. In a marking device, a body member including a handle portion having a chamber therein, a type holding member, means to mount said type holding member for sliding movement in the chamber, said type holding member having a hole extending downwardly from the upper surface and a pin including a body slidable in said hole, said pin having a reduced outer end portion, and means normally urging the pin upwardly in the hole, said body having an elongated slot positioned to receive the reduced portion of the pin, said body having an inwardly open recess, said recess being of a size to receive the body of the pin, the total length of said pin being no greater than the depth of said hole whereby the pin may be depressed inwardly so that its outer end is below the inner face of the top of the handle chamber to permit assembly and disassembly, the reduced end of said pin being slidable in said slot to permit said type holding member to be moved so that type may be inserted, the enlarged portion of said pin being movable into said recess to releasably hold the type holding member in retracted position, said type holding member having a type receiving pocket therein.

3. In a marking device, a body member including a handle portion having a chamber therein, said chamber having an open end, a type holding member slidable into the open end of the chamber, said type holding member having a cylindrical hole extending downwardly from the upper surface thereof, a pin slidable in said hole, said pin having a reduced cylindrical upper end portion, means normally urging the pin upwardly in the hole, said body having an elongated, round ended slot positioned to receive the reduced portion of the pin, said slot having closed ends, said body, at the top of said chamber, having a cylindrical inwardly open recess located adjacent to the inner end of said slot, said recess being of a size to receive the body of the pin, the total length of said pin being no greater than the depth of said hole whereby the pin may be depressed inwardly so that its outer end is below the inner face of the top of the handle chamber to permit assembly and disassembly, the reduced end of said pin being slidable in said slot to permit said type holding member to be moved to permit type to be inserted and to be secured, the enlarged portion of said pin being movable into said recess to hold the type holding member retracted, said type holding member having a type receiving pocket therein.

4. In a marking device, a body member including a handle portion having a chamber therein, a type holding member, means to mount said type holding member for sliding movement in the chamber, said type holding member having a hole

extending downwardly from the upper surface, a pin including a body slidable in said hole, said pin having a reduced upper end portion, and means normally urging the pin upwardly in the hole, said body having an elongated slot positioned to receive the reduced portion of the pin, said body, in the inner upper wall of said chamber, having an inwardly open and outwardly closed recess located adjacent to the inner end of said slot, said recess being of a size to receive the body of the pin, the total length of said pin being no greater than the depth of said hole whereby the pin may be depressed inwardly so that its outer end is below the inner face of the top of the handle chamber to permit assembly and disassembly, the reduced end of said pin being slidable in said slot to permit said type holding member to be moved so that type may be inserted, the enlarged portion of said pin being movable into said recess to releasably hold the type holding member in retracted position, said type holding member having a type receiving pocket therein.

5. In a marking device, a body member including a handle portion having a chamber therein, a type holding member, means to mount said type holding member for sliding movement in the chamber, said type holding member having a cylindrical hole extending downwardly from the upper surface and terminating short of the lower surface thereof, a cylindrical pin including a body slidable in said hole, said pin having a reduced cylindrical upper end portion, and means normally urging the pin upwardly in the hole, said body having an elongated slot positioned to receive the reduced portion of the pin, said body, in the inner upper wall of said chamber, having a cylindrical inwardly open and outwardly closed recess located at the inner end of said slot, said recess being of a size to receive the body of the pin, the total length of said pin being no greater than the depth of said hole whereby the pin may be depressed inwardly so that its outer end is below the inner face of the top of the handle chamber to permit assembly and disassembly, the reduced end of said pin being slidable in said slot to permit said type holding member to be moved so that type may be inserted, the enlarged portion of said pin being movable into said recess to releasably hold the type holding member in retracted position, said type holding member having an opened pocket therein, said pocket being defined by a bottom wall, an inner end wall, and side walls, said bottom wall having a transverse rib thereon.

6. In a marking device, a body member including a handle portion having a chamber therein, said chamber having a closed top, an open bottom and an open outer end, said body member having a groove along each side of the chamber, a type holding member having beads fitting said grooves and slidable into the open end of the chamber, said type holding member having a cylindrical hole extending downwardly from the upper surface and terminating short of the lower surface thereof, a cylindrical pin including a body slidable in said hole, said pin having a reduced cylindrical upper end portion and a spring beneath said pin and normally urging the pin upwardly in the hole, said body having an elongated, round ended slot positioned to receive the reduced portion of the pin, said slot having closed ends, said body, in the inner upper wall of said chamber, having a cylindrical inwardly open and outwardly closed recess located at the inner end

of said slot and coaxial with the end of and intersecting the slot, said recess being of a size to receive the body of the pin, the total length of said pin being no greater than the depth of said hole whereby the pin may be depressed inwardly so that its outer end is below the inner face of the top of the handle chamber to permit assembly and disassembly, the reduced end of said pin being slidable in said slot to permit said type holding member to be moved so that type may

be inserted, the enlarged portion of said pin being movable into said recess to releasably hold the type holding member in retracted position, said type holding member having an open ended 5 pocket therein, said pocket being defined by a bottom wall, an inner end wall, and side walls, said bottom wall having a transverse rib thereon and said side walls each having an arcuate notch therein.

10.

SAMUEL A. HAMNETT.
